UNITED STATES PATENT OFFICE.

EDWARD HAAS AND MILFORD B. FERGUSON, OF BROOKLYN, NEW YORK.

LABEL-FEEDING MECHANISM.

Original application filed May 12, 1922, Serial No. 560,365. Divided and this application filed November 10, 1923. Serial No. 674,063.

To all whom it may concern:

Be it known that we, EDWARD HAAS and MILFORD B. FERGUSON, citizens of the United States, residing at Brooklyn, in the county 5 of Kings, in the State of New York, have invented certain new and useful Improvements in Label-Feeding Mechanisms, of which the following is a specification.

The invention relates to an improvement 10 in label feeding mechanisms. The present application is a division of our copending application Serial No. 560,365, filed May 12, 1922.

The label feeding mechanism of the present invention is illustrated and described in said application as applied to and forming part of the novel wrapping machine which is the subject matter of said application, and for convenience the improved label feeding 20 mechanism is described and illustrated herein as applied to said wrapping machine. Only such parts of the wrapping machine are shown in the drawings as are necessary to bring out the connection between the 25 feeding mechanism and the wrapping machine. For a complete description of the relation between the mechanism and the machine, reference may be had to said application. Although the improved label feeding 30 mechanism is described and shown as applied to a wrapping machine, it will be understood that the invention is not to be restricted to this use inasmuch as it is adapted for application to and use in connection with 35 various other kinds of machines.

The object of the invention is to produce an improved label feeding mechanism having provision for transferring a label from one point to another on the same plane. 40 In the illustrated form of the invention the labels are supplied to the feeding mechanism on a horizontal plane and are transferred on that plane from the point at which the feeding mechanism receives the labels to the 45 point at which they are delivered to the wrapping or other machine to which the labels are to be delivered. The improved label feeding mechanism is also adapted for transferring labels from one point to another on other than the horizontal plane. The labels are supplied to the mechanism for transfer to the machine for acting upon them one at a time and this may be done by any preferred label supplying means. The 55 novel features of the invention include a

platform, means for actuating the platform to transfer the label from the receiving point to the point of delivery, means for properly positioning the label on the platform, means for clamping the label on the platform during the transferring movement and means for releasing the label when it has been properly positioned to be acted upon by the machine to which it is delivered. The invention is more fully described hereinafter 60 and is particularly pointed out in the appended claims.

The preferred form of the invention is illustrated in the accompanying drawings, in which Fig. 1 is a vertical section through 70 the improved label feeding mechanism, together with an elevation of certain of the parts of the wrapping machine to which the label feeding mechanism is shown applied in said application; Fig. 2 is a plan of the label 75 feeding mechanism (with certain of the actuating parts removed) showing the platform in position to receive a label; Fig. 3 is a view similar to Fig. 2 with the platform turned at an angle of 90° to deliver the label 80 to the machine to which the feeding mechanism is applied; Fig. 4 is a side elevation of certain of the actuating parts; Fig. 5 is a front elevation of the rolls, and associated parts, for supplying the labels one at a time 85 to the feeding mechanism; and Fig. 6 is a transverse section across the label guide.

The improved label feeding mechanism comprises a platform 1 supported on a bracket 2 secured to the lower end of a vertically arranged shaft 3 journaled in a hub 4 integral with a bracket 5 which is supported from a part of the wrapping machine to which the label feeding mechanism is supplied. The platform 1 is arc-shaped and is 90 of such length that while one end is delivering a label in the desired position to the wrapping machine the other end may act as a guide for the next label to be supplied to the mechanism. In the illustrated embodiment of the invention the labels are supplied to the mechanism at right angles to the position at which they are delivered to the wrapping or other machine. 100

The platform 1 is shown in Fig. 2 in position to receive a label 6 from the label supplying means. Fig. 3 shows the position of the platform as it holds the label at the point of delivery to the wrapping machine. This movement through an angle of 90° is 105 110

imparted to the shaft 3 and to the platform by means of a cam 7 mounted on a cam shaft 8 which is actuated from a source of power not shown. The connections between the cam 7 and the shaft 3 comprise an arm 74 secured to the shaft 9 and carrying on its free end a roll 75 which travels in a cam path formed in the side of the cam 7. On one end of the shaft 9 is mounted a bevel gear 10 which meshes with and drives a bevel pinion 11 secured to the upper end of shaft 3. These parts are arranged to move intermittently in timed relation with the movements of the machine to which the labels are delivered.

When the platform has delivered a label 6 as is shown in Fig. 3 and has swung back to the position shown in Fig. 2 to receive the next label, the turned-up edge 12 of an end extension 13 adjustably secured to the platform engages the label which has just been supplied to the mechanism and presses it against the inner side of an adjustable guide 14 secured to and extending toward the feeding mechanism from the frame 15 of the wrapping machine. By this means the label is properly positioned on the platform. Thereupon the clamp arm 16 provided at its free end and with a felt gripping means 17 is actuated to press and hold the label firmly against the platform.

The clamp arm 16 is pivotally mounted at 18 on an ear 19 rising from the bracket 2. The clamp arm 16 is actuated to hold the label against the platform and to release the label by means of a cam 20 mounted on the cam shaft 8. The connections between the cam 20 and the clamp 16 comprise a cam roll 21 carried by the upper end of a rod 22 which is bifurcated and straddles the cam shaft 8. The lower end of the rod 22 (which is adjustable in length) is pivotally connected with a horizontally disposed link 23 pivotally connected at its other end with a boss 24 depending from the bracket 5. The link 23 is provided with a lug carrying a pin 25 which is engaged in a groove formed in a collar 26 loosely mounted on the shaft 3. Also engaged in the grooved collar 26 is a pin 27 projecting laterally from the clamp arm 16. Thus the active part of the cam 20 serves to raise the clamp arm 16 and release the label. This occurs when platform 1 and the label 6 are in the position shown in Fig. 3. The clamp is depressed to hold the label against the platform by force of gravity. Thus the roll 21 is held in contact with the cam 20 by the weight of the parts connected with it.

The means for supplying the labels one at a time to the improved label feeding mechanism comprises a platform 28 upon which the labels are stacked, as shown in Fig. 1. The platform 28 is mounted on the upper end of a vertically arranged rack 29 which

is yieldingly pressed upwardly. This construction, which is supported from the front of the wrapping machine by a bracket, is well-known and requires no further description. The labels are pressed upwardly 70 against the holding needle 30 supported on an arm 31 adjustably secured in a bracket 32. The labels are stripped from the pile and delivered to the machine one at a time by a rubber, ratchet-controlled, wheel 33 75 when the pawl 34 is in engagement with the ratchet wheel 35. When the pawl 34 is out of engagement with the ratchet wheel, the rubber wheel 33 travels back and forth on the pile of labels without delivering them. 80 The wheel 33 is carried by the offset end of a lever 36 pivotally mounted on the lower end of an arm 37 secured to the shaft 38 journaled in brackets 39. The wheel 33 is yieldingly held in engagement with the pile of labels by a spring 40. The arm 37 is oscillated to cause wheel 33 to travel back and forth on the pile of labels by means of a crank 41 (Fig. 5) mounted on a shaft 42 journaled in the front of the machine. 85 The crank 41 is connected by a link 43 with the lower end of an arm 44, the upper end of which is secured to the shaft 38.

The leftward movement of the wheel 33 (viewing Fig. 1) serves to insert the top-most label between the upper and lower rolls which deliver the label to the feeding mechanism. The upper set of rolls 45 (Fig. 5) are mounted on the shaft 42 and travel in a clockwise direction, viewing Fig. 1. 100 The lower set of rolls 46 are secured to a shaft 47 journaled in the forward ends of arms 48 pivotally mounted on a bracket 49. The rolls 46 are held in yielding engagement with the rolls 45 by means of the spring 50. 105 The rolls 46 are driven in a counter-clockwise direction and for this purpose the shaft 42 is provided with a gear 51 which meshes with a gear 52 mounted on shaft 47. The left hand end of the shaft 42 carries a bevel gear 53 which meshes with a corresponding gear 54 fixed on a shaft 55 journaled in the machine frame, and which carries a sprocket wheel 56 which is driven by a second sprocket wheel 57 mounted on the cam shaft 110 8. The sprocket wheels are connected by a chain 58. Proper tension is imparted to the chain by an idler sprocket 59 mounted on the stud 60.

The feed rolls 45 and 46 deliver the label 120 in position to be clamped against the platform 1. The labels vary in length and some labels are of such length that it is not expedient that they pass entirely through the feed roll before they are gripped and swung into the desired position. When this is the case, and in order that the labels may move freely from between the feed rolls, the shaft 42 is provided with a cam 61 (Fig. 5), the active part of which is 125 130

- adapted to contact with a roll 62 mounted on the shaft 47 and thereby swing the shaft 47 downwardly and the rolls 46 out of contact with the label and the rolls 45. When 5 the active part of the cam 61 has passed out of engagement with the roll 62, the spring 50 returns gear 52 and rolls 46 to normal position in engagement with gear 51 and rolls 46.
- 10 As the label is swung from the point where it is supplied to the mechanism to the point where it is to be delivered to the wrapping or other machine, it passes between upper and lower guide rods 63 and 15 64 (Fig. 1). The feed rolls 45 and 46 supply the labels to the feeding mechanism between an upper guide 65 having an upturned forward end 66 and a lower guide 67. The swing of the platform into position to 20 receive the label and into the desired position to deliver the label is determined respectively by the stop rods 68 and 69.
- Having thus described the invention what we claim as new is:—
- 25 1. A label feeding mechanism having in combination with means for supplying a label to the mechanism, a platform mounted to move on a horizontal plane, said platform extending from the point where it receives 30 the label to the point where it delivers the label, means for oscillating the platform, and means for holding the label against the platform while the latter is moved to deliver the label.
- 35 2. A label feeding mechanism having in combination with means for supplying a label on a horizontal plane to the mechanism, a platform of which a part serves as a guide as the label is supplied to the mechanism, 40 means for moving the platform into label receiving position and into label delivering position, means for holding the label against the platform while it is moved from the receiving to the delivering position, and 45 means for actuating the holding means to release the label when it is in position to be delivered.
3. A label feeding mechanism having in combination with means for supplying a label to the mechanism, a platform mounted to swing on a horizontal plane through an angle of substantially 90°, said platform being of such length that while one end is holding a label in delivering position the other end acts as a guide for the incoming label, means for holding the label against the platform while it is swung from the receiving to the delivering position, and means for actuating the holding means to release 50 the label.
4. A label feeding mechanism having in combination with means for supplying a label to the mechanism, a platform arranged to swing through an angle of substantially 90° to transfer the label from the receiving 55 60 65 70 75 80 85 90 95 100 105 110 115 120 125 130
- to the delivering position, said platform being of such length that while it is delivering the label a part of the platform acts as a guide for the incoming label and by which the label is supported while the platform swings to receiving position, and means for actuating the platform.
5. A label feeding mechanism having in combination with means for supplying a label to the mechanism, a platform for transferring the label from the point at which it receives the label to the point at which the label is to be delivered, said platform being of such length that it extends from the one point to the other so that while one part of the platform is delivering a label the other part acts as a guide for the incoming label, and means for actuating the platform.
6. A label feeding mechanism having in combination with means for supplying a label to the mechanism, a platform for receiving the label, means for actuating the platform to move it from the point at which the label is received to the point at which the label is delivered, said platform having an upstanding edge adapted to be brought against one edge of the label when the platform returns to label receiving position, and means acting to hold the label against the platform as the latter moves from receiving to delivering position and to release the label when the platform is in delivering position.
7. A label feeding mechanism having in combination with means for supplying a label to the mechanism, a platform for transferring the label from the point at which it is received by the mechanism to the point at which it is delivered, a guide, said platform having an upstanding edge which is adapted to be brought against one edge of the label as the platform is moved to receiving position to move the label against the guide, means for clamping the label against the platform after it is positioned, means for actuating the platform, and means for releasing the clamping means when the platform is in delivering position.
8. A label feeding mechanism having in combination with means for supplying a label to the mechanism, a platform having a raised edge, a guide, means for actuating the platform to bring the raised edge against one edge of the label to position the label between the guide and the raised edge, means for holding the label against the platform while it is moved to position the label at the desired point, and means for holding the label against the platform while the platform is moved to the point at which the label is delivered.
9. A label feeding mechanism having in combination with a platform having a raised edge, a guide, said platform extending from the point where the label is delivered to the point at which it is received,

means for actuating the platform, the raised edge being brought against one edge of the label to push the label against the guide to properly position the label on the platform,
5 means for holding the label against the platform while the latter moves to the point at which the label is delivered, means for actuating the holding means to release the label, and means for supplying a label to the
10 platform while the first label is being delivered.

10. A label feeding mechanism having in

combination with means for supplying a label to the mechanism, a platform, a clamp arm pivotally mounted on the platform to 15 hold the label against the platform while it is swung from the point of receiving the label to the point at which the label is delivered, means for actuating the arm to release the label, and means for actuating the plat- 20 form.
